UNITED STATES PATENT OFFICE.

JOSEPH E. PRYOR, OF SUMMIT, NEW JERSEY.

GOLF-TEE ANCHOR.

Application filed December 13, 1926. Serial No. 154,460.

This invention relates to improvements in means separably attachable to ready-made golf-tees whereby the latter is conserved for repeated use.

5 The invention has for its principal object to provide an anchor device which may be readily attached to my ready-made golf-tee having a ground penetrating shank (of which there are several types on the market), and which, when so attached, conserves the tee for repeated use by holding the same against undue flight if it should be struck by the player when driving a ball supported thereby, thus substantially eliminating risk of loss of the tee during play, 10 and also diminishing the undesirable scattering of tees on the playing course or links, where their presence is detrimental to lawn mowers used in keeping the course in condition.

15 The invention has for a further object to provide a tee anchoring device comprising an anchor element and a flexible chain connection, the latter having a novel construction of means for detachably coupling or connecting the same with the shank of a ready-made tee for the purposes above mentioned.

20 The invention is clearly illustrated in the accompanying drawings, in which:—

25 Figure 1 shows a golf-tee supported on the ground and in turn supporting a golf-ball ready for play, the shank of said tee having connected therewith the novel anchoring device made according to and embodying the principles of this invention; Figure 2 is a sectional view, taken on line 2—2 in said Figure 1; and Figure 3 is an enlarged perspective view of the coupling 30 device for separably attaching the anchoring device and golf-tee together.

35 Similar characters of reference are employed in all of the hereinabove described views, to indicate corresponding parts.

40 Referring now to said drawings, the reference character 5 indicates the ball-supporting head of any suitable form of ready-made golf-tee, the same having in axial depending relation to said head 5 a ground 45 penetrating shank 6, which when thrust in the ground positions the head 5 to operatively support the ball 7 ready for play, all as shown, more especially, in Figure 1 of the drawings.

50 The tee anchoring device per se comprises an anchor element 8, which may consist in

a plate-like body of any suitable peripheral shape, and preferably made of metal to provide a drag-weight sufficient to substantially impede the flight of the tee should the same 60 be struck by the player when driving the ball. Said anchor element is provided with a perforate portion 9 to receive the connection of a flexible tie-member or connection 10, which is preferably made in the form 65 of a metallic chain, and which by its weight adds to the weight of the anchor element 8 as a drag upon or impediment to the flight of the tee should the same be struck by the player as aforesaid. Connected with the 70 free end of the tie-member or connection 10 is a coupling member for separable engagement with the shank 6 of the tee, to thus couple or secure the anchoring device and tee together in operative relation. This 75 coupling member comprises a metallic body which is doubled on itself to provide a base or back-plate 11 and a spring clamp-plate 12. The base or back-plate 11 is somewhat longer than the spring clamp-plate 12 to 80 provide an exposed perforate free end portion to receive the attachment thereto of the free end of the tie-member or chain 10. The spring clamp-plate 12 is provided intermediate its ends with a transversely disposed outwardly bowed portion 13 which forms at the inner face thereof a receiving 85 groove or channel 14 (see Figure 3.)

To apply the anchoring device to the golf-tee, the shank 6 of the latter is thrust downwardly through the receiving groove or channel 14 to lie intermediate the back-plate 11 and the clamp-plate 12. The tension of said clamp-plate 12 tends to thrust the tee-shank 6 laterally against the back-plate 11, whereby said shank is strongly gripped between the clamp-plate and back-plate, and thus frictionally bound against displacement from operative assembled relation to the anchoring device. The receiving groove or 90 channel 14 so embraces the tee-shank 6 as to prevent displacement of the tee from desired perpendicular or up-standing relation to the coupling member.

95 It will be apparent from the above description that the anchoring device may be readily attached to or removed from any ready-made tee having a ground penetrating shank.

A golf-tee equipped with the novel anchoring device may be thrust into the ground, as shown in Figure 1, so as to occupy an oper-

2
ative position adapted to support the ball 7 ready for play. If, in play, the player should inadvertently strike the tee, while it may be dislodged from engagement with 5 the ground, it will not tend to a long flight under the impulsion of the blow, since the anchoring device will quickly impede such flight, and will by its presence enable the player to quickly locate and recover the same 10 in event of such dislodgement.

The novel form of anchoring device I have invented lends itself admirably to production in precious or semi-precious metal, thus affording an attractive as well as useful article 15 to golf-players. The anchor element 8 may be variously treated to provide the same with any ornamental characteristics desired, e. g. it may be engraved or pierced to provide monograms thereon or other ornamental 20 embellishment, and it may be so made as to provide utilitarian features in addition to its function as an anchor device.

Having thus described my invention, I claim:—

25 1. An anchoring device for ready-made golf-tees, comprising an anchor element, a flexible tie to extend from said anchor element, and a coupling member connected with

the free end of said tie, said coupling member comprising a metallic body doubled longitudinally upon itself to provide a back-plate and an overlying clamp-plate tensionally related to said back-plate to cooperate therewith in frictionally gripping the shank of a golf-tee thrust therebetween. 30 35

2. An anchoring device for ready-made golf-tees, comprising an anchor element, a flexible tie to extend from said anchor element, and a coupling member connected with the free end of said tie, said coupling member comprising a metallic body doubled longitudinally upon itself to provide a back-plate and an overlying clamp-plate tensionally related to said back-plate to cooperate therewith in frictionally gripping the shank 40 45 of a golf-tee thrust therebetween, and said clamp-plate having an outwardly bowed transversely disposed portion intermediate its ends to provide an internal groove to embrace the engaged golf-tee shank and support the same against displacement from desired vertical position. 50

In testimony, that I claim the invention set forth above I have hereunto set my hand this 23rd day of October, 1926.

JOSEPH E. PRYOR.
